UNITED STATES PATENT OFFICE

VICTOR LEFEBURE, OF LONDON, ENGLAND

DECORATED TILE AND PROCESS OF MAKING THE SAME

No Drawing. Application filed March 9, 1928; Serial No. 260,549, and in Great Britain March 11, 1927.

In my specification No. 1,650,080 I have described a process of manufacture of decorative tiles by pressing or fixing on to a suitable backing with heating to a moderate temperature, a sheet which consists chemically of reacting ingredients, namely (1) silicates, and (2) compounds which will react with them, such as oxides, with fibrous or other fillers. The reacting ingredients in the processes described form a highly resistant decorative layer of plain colours, mottled and similar effects, which can also be used without backing.

According to the present invention, I obtain a layer exhibiting not only the above decorative effects, but also any designs and similar effects which can be obtained by printing or other similar mechanical operations, such as stencilling, transferring and like processes, all of which I class under the term printing. It amounts in principle to forming the decorative layer in a different manner, but leading at the end of the process to essentially the same type of layer, with greater range of decorative effect.

Low heats, with or without pressure, are again employed as in the previous specification above cited, to produce the final decorative layer. I work at temperatures below the upper limit of about 350° C. The mix can be adjusted to react at much lower temperatures, so that the most convenient range to produce the effects varies from room temperature to the above upper limit. For instance, zinc oxide is best employed for temperatures between 135° C. and 350° C., whereas substitution of zinc carbonate permits the reaction to occur at room temperatures.

In carrying out my invention, a fibrous layer comprising paper, asbestos paper, fabric or the like is impregnated with the reacting ingredients, and the decorative effect required is printed on the surface of the fibrous layer by means of a printing ink comprising only colours and ingredients compatible with the reaction in question are employed, the ink or paste consisting usually of the reacting ingredients with colours and other fillers. The colours can be of such a nature that owing to their fine state of division, or to their staining power, they penetrate the fibrous layer.

Various methods of proceeding may be adopted, as indicated hereafter. The tile, according to the invention, comprises therefore two juxtaposed elements of similar material, with or without a backing. Regarding the fibrous layer, such as asbestos paper, this can be made so that it contains one or all of the reacting ingredients, or fillers to give colour, hardness, etc. These, particularly the solid ingredients, can be introduced on the mill in the standard manner in which, for example, mineral fillers are introduced into paper; or one or any of the above ingredients suited to the purpose can be introduced by precipitation methods, such as, for example, the introduction of an oxide or hydroxide by impregnating with the chloride and precipitating the oxide or hydroxide by immersion in a base, such as an alkali; or liquid agents can be introduced by impregnation, such as, for example, the alkaline silicate.

Regarding the printing on the fibrous layer, I can either print with a medium which contains not only the colour but adequate proportions of the reacting ingredients, or I can print with some of these ingredients and introduce the remainder by such methods as immersion in the liquid, or spraying it on to the surface or in cases where the colour penetrates, I need not employ the reactants in the ink when they already exist in the paper or the like.

A typical printing medium would contain alkaline silicate, zinc oxide, or other reacting compound, a filler such as silica, pigments for colour, and any modifying agent required to suit the needs of the particular kind of printing, such as glycerol to resist rapid drying,

or sticky agents such as dextrine to give the requisite tacky quality. As an example, a suitable ink would consist of the following: alkaline silicate solution (about 40% of solid) 5 —4 parts, zinc oxide—3 parts, ultramarine blue— $\frac{1}{2}$ part, silica—1 part, glycerol— $\frac{1}{2}$ part.

It is obvious that to obtain a desired effect, the order of the above operations can be 10 changed to meet individual cases.

I give below a list of suitable combinations or methods, with a more detailed description of one particular method; but it is clear that modifications will be possible, so I do not bind 15 myself rigidly and only to the use of the methods indicated.

(1) First, a fibrous layer is taken, such as asbestos paper, which contains the solid reacting ingredient such as zinc oxide, and any 20 fillers, such as silica, or china clay, or pigments, which have been introduced into the fibre by standard methods such as adding fillers in a paper mill, or by precipitation, as indicated above. The fibrous layer is now 25 impregnated with alkaline silicate, yielding a layer which will react as above to a hard resistant mass. On to this layer I print the required design, using an ink which also contains the reactants and the necessary colour 30 and any fillers required, as, for example, to facilitate printing.

(2) Secondly, I may take a fibrous layer from which one of the reactants is absent, such as the alkaline silicate, and print on it 35 with an ink in which the same reactant is also absent. The absent reactant can then be introduced into the decorative layer, such as by impregnation with alkaline silicate, resulting in the same type of layer as (1) above.

(3) Thirdly, the completely filled fibrous 40 layer as in (1) above may be printed with inks which simply penetrate and stain the layer.

(4) In the case of very thin fibrous layers, 45 the liquid reactant, i. e., alkaline silicate, may be omitted from the fibrous layer, but the complete ink may be used, which in the act of printing on the fibrous layer enables the silicate to penetrate the latter, and again leads 50 to the same result.

(5) Or an ink may be employed which contains the reactants and fillers except the alkaline silicate, and printed on the complete fibrous layer as in (1) above. In this case, the 55 alkaline silicate penetrates the ink after printing, and again leads to the same final layer. This method is suitable when the finished article is to be submitted to high pressures, which facilitate the impregnation of 60 the ink.

(6) I can also print with the complete ink direct on to a rigid base, such as smoothed asbestos cement.

(7) I can also print with the complete ink 55 direct on to the fibrous layer and rely upon

the reacting ingredients in the ink to penetrate the fibrous layer, as they will do in special cases, such as a very absorbent fibrous layer, and/or thick printing coats.

The above enumeration, which is not intended to be exhaustive, refers to various possible manners of carrying out the invention. In the following example one particular method will now be described in greater detail.

Example.—Asbestos paper is manufactured, incorporating during manufacture zinc oxide as one of the reactants, and if desired, china clay, or silica, or similar fillers, to reduce the absorption of the paper and give hardness, for example, 40% zinc oxide, 10% silica, 5% colours. This paper may now be impregnated with alkaline silicate solution, or this operation may be deferred as below. On the surface of the paper, a design is printed in a medium consisting of a mixture of alkaline silicate, zinc oxide or zinc salt, colour and any other fillers, such as inert fillers, to give appropriate body to the ink, or small percentages of modifying agents such as glycerol or oily substances, to facilitate printing. For thick layers which have not been previously impregnated with alkaline silicate solution as above, and, where the silicate in the ink may not penetrate sufficiently deeply, a further immersion, or spraying, on one or both sides, with the silicate is necessary.

This provides the decorative layers ready to be heated and/or pressed, preferably on to a suitable rigid backing to give the resistant decorative article, the layer being secured to the rigid backing by a junction such as that used in accordance with the parent specification. Where greater strength is required in the fibrous decorated layer, I can give it greater strength by metallic reinforcement, as for example by metallic netting.

The preferred form of my invention consists in a tile manufactured by heating and/or pressing the fibrous decorated layer upon asbestos cement, which may or may not be suitably backed.

What I claim and desire to secure by Letters Patent is:—

1. A process of manufacture of decorated tiles and like articles, of the kind consisting of two juxtaposed elements, and manufactured by pressing, with heating to a moderate temperature, a sheet consisting of a fibrous layer in which are incorporated reacting ingredients, namely (1), silicates and (2) compounds which react with them to form a hard resisting compound, and fillers, which process consists in producing on the surface of the tile a decorated effect by means of printing material adapted to finally form on the fibrous layer a hard resisting compound similar to that of the said sheet.

2. A process of manufacture of decorated

5 tiles and like articles, as claimed in claim 1, in which only one of the reacting ingredients is at first present in one of the juxtaposed elements and the other is introduced into this said element by passing into it from the other element when juxtaposition takes place.

10 3. A process of manufacture of decorated tiles and like articles, as claimed in claim 1, in which only one of the reacting ingredients is at first present in the fibrous layer and the other is introduced into this said element by passing into it from the other element when juxtaposition takes place.

15 4. A process of manufacture of decorated tiles and like articles, as claimed in claim 1, in which the compound reacting with silicate is alone present in the fibrous layer, the other reacting ingredient being introduced into the said layer by passing into it from the ink 20 when juxtaposition takes place.

25 5. A process of manufacture of decorated tiles and like articles, as claimed in claim 1, in which only one of the reacting ingredients is at first present in both the juxtaposed elements and the other is introduced simultaneously in both after juxtaposition through a suitable treatment such as sprinkling.

30 6. A process of manufacture of decorated tiles and like articles, as claimed in claim 1, in which both the reacting ingredients are present in one only of the juxtaposed elements and are introduced in the other when juxtaposition takes place.

35 7. A process of manufacture of decorated tiles and like articles, as claimed in claim 1, in which both the reacting ingredients are present in one only of the juxtaposed elements and are introduced in the other when juxtaposition takes place by passing from the first said element into the second said element.

40 8. A process of manufacture of decorated tiles and like articles, as claimed in claim 1, in which both the reacting ingredients are at first present only in the ink and are introduced into the fibrous layer owing to its porosity by penetrating into it from the other element when juxtaposition takes place.

45 9. A process of manufacture of decorated tiles and like articles, in which a decorative effect is obtained on a rigid base by means of a printing material comprising reacting ingredients, namely (1), silicates and (2) compounds which react with them to form a hard resisting compound, and fillers, so as to form on the said base a hard resisting compound.

50 10. A process of manufacture of decorated tiles and like articles, as in claim 8 in which the decorative effect is obtained on a fibrous layer comprising reacting ingredients, namely (1), silicates and (2) compounds which react with them to form a hard resisting compound, and fillers, by means of ordinary printing ink.

55 11. A process of manufacture of decorated tiles and like articles, as claimed in claim 1, in which the two juxtaposed elements are pressed onto a suitable backing, while hot, during the process of manufacture.

60 12. A process of manufacture of decorated tiles and like articles, as claimed in claim 1, in which the two juxtaposed elements are pressed onto a suitable backing of asbestos cement, while hot, during the process of manufacture.

65 13. Decorated tiles consisting of a resisting compound comprising a decorated sheet consisting of a fibrous layer in which are incorporated reacting ingredients, namely (1) silicates and (2) compounds which react with them to form a hard resisting compound and fillers on which the decorative effect on the sheet consists of printing material containing similar reacting ingredients and fillers, so as to form a resisting compound similar to that of the said sheet.

70 14. Decorated tiles consisting of a resisting compound comprising a suitable backing and, pressed hot onto the said backing, a decorated sheet consisting of a fibrous layer in which are incorporated reacting ingredients, namely (1) silicates and (2) compounds which react with them to form a hard resisting compound and fillers on which decorative effect on the sheet consists of printing material containing similar reacting ingredients and fillers, so as to form a resisting compound similar to that of the said sheet.

75 15. Decorated tiles consisting of a resisting compound comprising a rigid base on which the decorative effect consists of an ink containing reacting ingredients, namely (1) silicates and (2) compounds which react with them to form a hard resisting compound, and fillers.

80 16. Decorated tiles consisting of a resisting compound comprising a decorated sheet consisting of a fibrous layer in which are incorporated reacting ingredients, namely (1) silicates and (2) compounds which react with them to form a hard resisting compound, and fillers on which the decorative effect consists of ordinary printing ink.

85 17. Decorated tiles consisting of a resisting compound comprising a decorated sheet consisting of an absorbent fibrous layer in which are incorporated reacting ingredients, namely (1) silicates and (2) compounds which react with them to form a hard resisting compound and fillers on which the decorative effect on the sheet consists of printing material containing similar reacting ingredients and fillers, so as to form a resisting compound similar to that of the said sheet.

90 18. Decorated tiles consisting of a resisting compound comprising a decorated sheet consisting of an absorbent fibrous layer in which are incorporated reacting ingredients,

namely (1) silicates and (2) compounds which react with them to form a hard resisting compound and fillers on which the decorative effect on the sheet consists of printing material containing similar reacting ingredients and fillers, so as to form a resisting compound similar to that of the said sheet, the said printing material being of great fluidity and its fillers being in a fine state of division, so as to easily penetrate the absorbent fibrous layer.

In testimony whereof, I affix my signature.
